United States Patent

Des. 242,251
Patented Nov. 9, 1976

242,251

DENTAL SYRINGE

Sven Karl Lennart Goof, 46C Marielundsvæj,
DK-2730 Herlev, Denmark

Filed Sept. 12, 1974, Ser. No. 505,578

Term of patent 14 years

Int. Cl. D24—02

U.S. Cl. D24—1 D

FIG. 1

FIG. 2

FIG. 3

FIG. 4

FIG. 5

FIG. 6

FIG. 7

FIG. 8

FIG. 9

FIG. 10

FIG. 1 is a side elevation of a dental syringe showing my new design;

FIG. 2 is an elevation as seen from the side opposite FIG. 1;

FIG. 3 is a front elevation thereof;

FIG. 4 is a side elevation of the syringe tip shown separately for clarity of illustration;

FIG. 5 is an elevation as seen from the opposite side of FIG. 4;

FIG. 6 is a front elevation thereof;

FIG. 7 is a rear elevation thereof;

FIG. 8 is a side elevation of the dental handpiece shown separately for clarity of illustration;

FIG. 9 is an elevation of the side opposite that illustrated in FIG. 8; and

FIG. 10 is a front elevation thereof.

I claim:

The ornamental design for a dental syringe, as shown.
